UNITED STATES PATENT OFFICE.

JOSEPH W. BETTENDORF, OF BETTENDORF, IOWA.

JOURNAL-BOX LID.

Application filed August 23, 1926. Serial No. 130,845.

This invention relates to journal boxes and more particularly to lids therefor.

An object of this invention is to provide a journal box lid which can be readily made with an integral pintle pin to cooperate with standard journal box hinge lugs.

Another object of this invention is to provide a lid with an integral pintle pin which can be readily applied to and removed from journal boxes equipped with standard journal box hinge lugs, when the journal boxes are attached to the side frame of a car, and which may carry a suitable spring to hold the lid in closed or open position.

Another object of my invention is to provide a rigid cover structure, or journal box lid, wherein a lid body portion, pintle, and connecting straps are associated together as a unit.

These and other objects of my invention will be apparent from the following description and annexed drawings, in which:

Figure 1 is a front elevation of my journal box lid;

Fig. 2 is a vertical section on line 2—2, Fig. 1, showing the lid applied to a journal box of standard construction;

Fig. 3 is a plan view of the blank from which the lid is formed;

Fig. 4 is a front elevation of a modified form of lid;

Fig. 5 is a horizontal section on line 5—5 of Fig. 4;

Fig. 6 is a side elevation of the lid;

Fig. 7 is a fragmentary section on line 7—7 of Fig. 4; and

Fig. 8 is a plan view of the blank used to form the lid shown in Fig. 4.

Fig. 9 is a fragmentary side elevation of that portion of the journal box showing the hinge lug.

In Fig. 1 is shown a journal box lid which is of the same general construction as shown in the Bendixen Patent, 1,472,785, granted November 6, 1923.

Integral with the body portion 1 of the journal box lid are the usual side flanges to fit over the journal box. At the sides of the upper marginal portion of the lid are offset connecting straps 3 to which is joined the integral pintle member 4, which is similarly offset from the body portion of the journal box lid. Preferably wings 5 extend from the metal forming the pintle member

4, and these wings may be bent back to overlie the offset portions of the connecting straps 3 and to extend up and onto the face of the body of the journal box lid. The body portion 1 and straps 3 and pintle member 4 are thus associated together and function as a unit.

The portions 6 of the extension wings 5 reinforce and make the connecting straps considerably more rigid and these portions may be spot welded to the body of the lid and to the connecting straps if desired.

The connecting straps and pintle form with the body of the lid an aperture 1^a to receive the forward or outer portions of a standard hinge lug mounted on the journal box as will be more fully described hereinafter.

The body of the journal box lid may be stiffened by suitable depressions 7, 8, and 9 as is well understood, and the finger piece 10 is provided for readily opening and closing the lid against the pressure of the spring 11. The spring 11 may be suitably attached to the lid in any desired manner, and is provided with a flat portion at the top to bear against the flattened portions 12, 13 of the journal box lug 14.

The journal box lug 14 comprises a standard lug with an eye portion 15 to receive a hinge pintle of standard diameter. Between the end portions 17 of the hinge lug are the flattened portions 12, 13 which are adapted to be engaged by the lid spring 11. It will be noted that the end portions 17 extend outwardly from the journal box sufficiently to form shoulders to prevent lateral movement of the journal box lid during opening or closing thereof.

The hinge lugs for journal box lids shown in the drawings are of standard construction as approved by The American Railway Association and have the eye of the hinge lug set back from the plane of the opening of the journal box and this necessitates the offsetting of the connecting straps and the pintle to provide a journal box lid which covers the journal box opening and that is turned in around all sides. It is obvious, however, that if the hinge lugs are not set back from the plane of the opening the pintle and connecting straps can be formed without the offset and will operate satisfactorily.

The standard hinge lug 14 is shown provided with a narrow slotted portion 18 connecting with the eye to receive the pintle 4 of the lid. The slot 18, of course, is narrower than the diameter of the pintle to prevent displacement of the pintle in service, and may be arranged substantially vertically of the journal box or at any desired angle, so that it does not interfere with the application of the journal box lid to the journal box or its removal therefrom when the journal box is attached to the side frame.

In order to apply the lid to the journal box, it is only necessary to raise the spring 11 sufficiently so that it will clear the projecting portions 17 of the ends of the hinge lug. The lid is then tilted until the connecting strap 3 between the pintle 4 and body of the lid is in alignment with the slot 18 and the pintle 4 is in alignment with the eye 15 of the hinge lug. The lid is then moved along the axis of the pintle until it is in position, when the spring 11 is released and the lid may be swung to open or closed position, as desired. It is obvious that the lid may be readily removed in the same manner, by simply raising the spring from the surface of the lid and sliding it longitudinally of the axis of the pintle out of engagement with the hinge lug.

The lid shown in Fig. 1 may be readily formed from a single plate of metal by first stamping a blank such as shown in Fig. 3. The side flanges 1^b of the lid are then folded at right angles to the body of the lid and the connecting straps 3 are folded to be offset from the body of the lid. The portion 2 of the blank is then folded or rolled to form a cylindrical pintle, and the wings 5 are pressed back against the connecting straps and into engagement with the face of the lid.

It will thus be seen that I have provided a journal box lid which is rigid in construction and which may be readily applied to or removed from a journal box without any danger of losing loose hinge pintles, cotter pins and the like, and that the lid may be readily formed from a single plate of metal with the hinge pin integral with the lid.

It will furthermore be noted that I have provided an advantageous unitary cover structure for a journal box in which a lid body portion, pintle, and connecting straps are associated together and operate as a unit.

In Figs. 4 to 6 a modified construction of journal box lid is shown. This construction is similar to that of Fig. 1, with the exception that the blank as shown in Fig. 8 is shorter because the portion 3' which is rolled to form the integral pintle 4' has no extensions or wings as is the case in the construction shown in the Figs. 1 to 3. The

metal which is rolled to form the integral pintle simply abuts the lower part of the pintle to substantially complete the rolled portion. Also to additionally reinforce the connection between the body portion 1' of the lid and the pintle 4' the portion of metal outside of the connecting straps is left intact so that the connecting straps 20 extend from the aperture 22 to the edge of the blank and taper up to the pintle 4' thus forming a triangular shaped reinforcing member 23. The connecting straps 20 are further provided with ribs or flutes 21 to make them more rigid. The body portion 1' of the lid may be similarly reinforced with depressions 7', 8', 9', and is provided with a similar finger piece 10'. The ribs 21, however, are not made deeper than a double thickness of the metal, so that the lid may be readily applied to a hinge lug of the same type and having a slot of the same size as that necessary for the construction shown in Fig. 2.

In this form of construction it will be seen that less metal is used to form the journal box lid as the blank required is shorter in that the wings or extensions used in the other constructions are omitted.

It will thus be seen that with either construction shown in this application I have provided a journal box lid with an integral pintle adapted to cooperate with journal box hinge lugs of usual construction, it being only necessary to form a suitable, outwardly opening, narrow slot in the lugs to connect with the eye portion. The lids may then be readily applied to or removed from the journal boxes when they are attached to railway car side frames, and thus disassembly of the railway car trucks is unnecessary to apply or remove the journal box lids.

It will also be seen that even if the standard hinge lugs are modified by incorporating a slot 18, this will not in any way prevent the use of the journal box lids now in common use as these lids with their removable pintles can be applied to or removed from the journal box in the ordinary manner and there will be no danger of the hinge pintle coming out of the narrow slotted portion 18 of the hinge lug.

While the journal box lids shown in the drawings are formed of pressed steel it is obvious that the lid, pintle and connecting straps can be cast as one integral unit if desired and that this is within the scope of my invention. If the lid be made of pressed steel it is obvious that the design can be widely varied and the lid shaped up in various methods.

Furthermore, it is to be understood that the particular forms of apparatus shown and described, and the particular procedure set forth, are presented for purposes of

explanation and illustration and that various modifications of said apparatus and procedure can be made without departing from my invention as defined in the appended claims.

What I claim is:

1. The combination with a journal box, of a journal box lid having a body portion and an integral pintle connected therewith by integral connecting straps at the sides of the upper margin of the lid, said straps and pintle defining with the body portion an aperture to receive a portion of the hinge lug of the journal box, said hinge lug having flattened portions and an outwardly opening slot to permit mounting of the lid in operative position on the journal box when the journal box is attached to the side frame of a car, and a spring secured to the face of the lid to bear against said flattened portions to hold the lid in open or closed position, the upper marginal portion of said lid terminating adjacent the base of the hinge lug.

2. The combination with a journal box of a journal box lid having a body portion and an integral pintle connected therewith by integral connecting straps at the sides of the upper margin of the lid, said straps and pintle being offset from the body portion of the lid and defining with the body portion an aperture to receive a portion of the hinge lug of the journal box, said hinge lug having an outwardly opening slot disposed at an angle to the lug so that the lid may be applied to or removed from the journal box when the journal box is attached to the side frame of a car, and a spring secured to the face of the lid to hold the lid in open or closed position, the upper marginal portion of said lid terminating adjacent the base of the hinge lug.

3. The combination with a journal box of a journal box lid having a body portion and an integral hollow pintle connected therewith by integral connecting straps at the sides of the upper margin of the lid, said straps and pintle defining with the body portion an aperture to receive a portion of the hinge lug of the journal box, said hinge lug having an outwardly opening slot disposed at such an angle that the lid may be readily applied to or removed from the journal box when the latter is attached to the side frame of a car, and spring means cooperating with the lid and journal box to hold the lid in open and closed position, the upper marginal portion of said lid terminating adjacent the base of the hinge lug.

4. A journal box lid having a body portion and a hollow cylindrical pintle integrally connected therewith by connecting straps at the sides of the upper marginal portion of the lid, said straps and pintle defining with the body portion of the lid an aperture adapt-

ed to receive a portion of the hinge lug of a standard journal box, the upper marginal portion of the body of the lid terminating substantially at the base of the hinge lug, and a spring secured to the outer face of the lid for engagement with said hinge lug.

5. A journal box lid having a body portion and a cylindrical pintle integrally connected therewith by connecting straps at the sides of the upper marginal portion of the lid, said straps extending beyond the upper marginal portion of the lid and together with the upper marginal portion of the lid defining an aperture to receive a portion of the hinge lug of a standard journal box, said integral straps and pintle being offset from the body portion of the lid, and a spring secured to the outer portion of the lid for engagement with said hinge lug.

6. A pressed metal journal box lid having a body portion adapted to engage the sides of a journal box forming the journal box opening, a pintle connected with said lid by integral connecting straps disposed at the sides of the upper marginal portion of the lid, said straps being reinforced to rigidly support the pintle, said pintle being spaced from the upper marginal portion of the lid whereby a portion of the hinge lug of the journal box may be inserted between the body portion of the lid and the pintle, and spring means secured to the outer face of the lid to bear against the hinge lug to hold the lid in open or closed position.

7. A pressed metal journal box lid having a body portion adapted to engage the sides of a journal box forming the journal box opening, a hollow cylindrical pintle integrally connected to the upper marginal portion of the journal box lid by reinforced integral connecting straps, said pintle being spaced from the upper marginal portion of the lid whereby a portion of the hinge lug of the journal box may be inserted between the body portion of the lid and the pintle, and spring means secured to the outer face of the lid to bear against the hinge lug to hold the lid in open or closed position.

8. The combination with a journal box, of a rigid unitary cover structure having a lid body portion and pintle and straps extending from the sides of the upper margin of the lid to the pintle, said straps and pintle defining with the body portion an aperture to receive a portion of the hinge lug of the journal box, said hinge lug having flattened portions and an outwardly opening slot to permit mounting of the lid in operative position on the journal box when the journal box is attached to the side frame of a car, a spring secured to the face of the lid to bear against said flattened portions to hold the lid in open or closed position, the upper marginal portion of said lid terminating adjacent the base of the hinge lug, and means

for preventing accidental movement of the lid longitudinally of the hinge lug when the lid is in open position.

9. The combination with a journal box, of
5 a rigid unitary cover structure having a lid body portion and pintle and straps extending from the sides of the upper margin of the lid to the pintle, said straps and pintle being offset from the body portion of the lid and
10 defining with the body portion an aperture to receive a portion of the hinge lug of the journal box, said hinge lug having an outwardly opening slot disposed at an angle to the lug so that the lid may be applied to or
15 removed from the journal box when the journal box is attached to the side frame of a car, and a spring secured to the face of the lid to hold the lid in open or closed position, the upper marginal portion of said lid terminating adjacent the base of the hinge lug.

10. The combination with a journal box,

of a rigid unitary cover structure having a lid, body portion and pintle and straps extending from the sides of the upper margin of the lid to the pintle, said straps and pintle defining with the body portion of the lid an aperture to receive a portion of the hinge lug of the journal box, said hinge lug having depressed portions and an outwardly opening slot to permit mounting of the lid in 25 operative position on the journal box when the journal box is attached to the side frame of a car, the upper marginal portion of said lid terminating at the base of the hinge lug, and a spring secured to the face of the lid to bear against said depressed portions to hold the lid in open or closed position, and means on the hinge lug to prevent accidental movement of the lid longitudinally of the hinge 30 lug. 35

In testimony whereof I affix my signature.
JOSEPH W. BETTENDORF. 40
